UNITED STATES PATENT OFFICE

GEORGE K. CHENEY, OF BALDWIN, NEW YORK

DESIGN FOR A FISHING LINE SINKER

Application filed May 13, 1932. Serial No. 43,796. Term of patent 7 years.

To all whom it may concern:

Be it known that I, GEORGE K. CHENEY, a citizen of the United States, residing at 34 Harvard Avenue, Baldwin, in the county of Nassau and State of New York, have invented a new, original, and ornamental Design for Fishing Line Sinker, of which the following is a specification.

In the accompanying drawing:

Figure 1 is a top plan view of a fishing-line sinker, showing my new design; Figure 2 is an end view thereof, and Figure 3 is a side view of the same.

I claim:

The ornamental design for a fishing line sinker, substantially as shown.

GEORGE K. CHENEY.
